UNITED STATES PATENT OFFICE.

ARVID ERICSSON, OF CHICAGO, ILLINOIS, ASSIGNOR TO UNION SPECIAL MACHINE COMPANY, OF CHICAGO, ILLINOIS, A CORPORATION OF ILLINOIS.

LAPPING MACHINE.

Application filed November 3, 1924. Serial No. 747,558.

This invention relates to lapping machines for ball joints, and the like, wherein it is desired to impart to one of the two members of the joint a prescribed wobbling movement 5 to insure the more perfect fitting and operation of the joint.

One of the objects of the present invention resides in providing a device for imparting a prescribed wobbling movement to one of 10 the two members to be lapped, which device is constructed so as to prevent objectionable vibrational motions tending to modify the desired movement.

Yet a further feature of the invention resides 15 in providing a rugged, compactly arranged device of the character described.

Another object of the invention resides in the arrangement of the rotatable bearing for firmly supporting the rotary inclined shaft 20 carrying one of the members to be lapped.

An additional object resides in the construction of the collet or chuck for holding the member to be lapped, which collet is arranged axially of the inclined shaft and is 25 operable from the rear or accessible end of the shaft.

A further feature of the invention resides 30 in the novel arrangement of the holder for the other member to be lapped whereby it may be held firmly in lapping position or swung to a position for withdrawing the member from its holder.

Yet a further feature of the invention lies 35 in the arrangement of the driving mechanism whereby one or more lapping devices may be driven at will from a common power shaft.

These and other objects will be apparent 40 from a perusal of the following specification when taken in connection with the accompanying drawings, wherein—

Figure 1 is a sectional view of one end of 45 the machine showing one complete lapping unit and its geared connection to the longitudinal power shaft;

Fig. 2 is a view taken on line 2—2 of Fig. 3;

Fig. 3 is an end view of Figure 1, and

Fig. 4 is the reverse end view of Figure 1.

Referring now to the drawings in detail, the device is preferably arranged as a gang machine for simultaneously lapping any 50 number of joints, each unit being driven from a common power shaft and being independently operable. Further, the inven-

tion is illustrated as a device for lapping ball joints of sewing machines, but obviously it is of general application.

The device comprises a relatively long casting formed at intervals along its length with 60 upright bearings to support the rotating shafts of each unit. Inasmuch as the separate units are similar, the description of one will suffice. For instance, in Fig. 1 the casting is shown as formed with a relatively 65 broad base 1 having an upturned flange 2 to catch the oil drippings. The base is provided with upstanding walls 3 and 4 supporting the bearings 5 and 6 for the power shaft 7, which is provided with the driving 70 pulley 8 on its outer end. As before mentioned, shaft 7 extends the entire length of the base.

Arranged preferably immediately above the power shaft 7 and preferably axially parallel thereto is a rotatable bearing 9. This bearing has one end rotatively mounted in the upper portion 10 of the upstanding wall 4 and to this end is provided with a bearing 11. The opposite end of the rotatable 80 bearing 9 is provided with an axially arranged bore to receive a short fixed shaft 12 mounted in an end cover 13 attached by suitable screws 14 to the upper housing 15 of the casting. This rotatable bearing 9 carries the inclined shaft 16 supporting one of the members to be lapped. To this end bearing 9 is formed with a bore disposed at an acute angle with respect to the axis of rotation of the bearing and shaft 16 is 85 rotatively mounted in this bore by means of the bearing sleeves 17 and 18. Shaft 16 in turn is provided with an axial bore, which bore is enlarged at the inner end as at 19 to house the collet or chuck 20 consisting of a 90 hollow sleeve having spring gripping fingers 21. The exterior surface of these fingers is preferably curved in order to protect the hands of the operator. One of the members of the ball joint adapted to be lapped, in the 95 present instance the ball member 22, provided with the threaded shank member 23, is seated in a countersunk bore in this chuck 21 and is held in desired position therein by means of a stop pin 24 which has threaded 100 engagement with the inner wall of the hollow chuck sleeve 20. Manifestly, by adjusting the stop pin 24 the correct position of the member 23 is secured. The chuck is 105 drawn into gripping engagement with the 110

member 23 by means of the wedge shaped faces 25 at the inner end of shaft 16 engaging the chuck fingers 21 and by means of a draw pin 26, the inner end of which is threaded to engage the chuck sleeve 20.

Means is provided for rotating the bearing 9 from the power shaft and for rotating the inclined shaft 16 in the rotary bearing 9.

In the preferred form, the power shaft 7 is provided with a spline 27 on which slides a member 28 of a clutch. This clutch member accordingly is formed with a sleeve 29 on which threads a nut 30 adapted to confine lugs 31 in position between a shoulder 15 on the clutch and a ball bearing 32. Lugs 31 are carried by the forks of a shifter lever 33 mounted on the end of a pivoted shaft 34 adapted to be oscillated through a lever 35 which lever is formed on its upper end with 20 a detent 36, spring-pressed to engage in a recess 37 (see Fig. 4). In this manner, the clutch can be locked in either position. A spring 38 housed in a counter bore 39 coils about shaft 7 and presses the clutch 28 normally into engagement with a cooperative clutch member 40 provided on its periphery with gear teeth 41 which mesh with teeth 42 formed on the periphery of the inner portion of the rotary bearing 9. The clutch 25 member 40 carrying the gear teeth 41 is mounted on a bushing 40^a. This clutch member is freely mounted on the bushing and is held from endwise movement on the shaft 7 by collars 40^a and 40^b, which are secured to the shaft by suitable set screws. This clutch member which is geared to the bearing 9, is connected to the shaft 7 by means of the clutch member 28, which clutch member is splined to the shaft and movable 30 longitudinally on the shaft into frictional gripping connection with this clutch member 40. Thus this bearing is rotated in its bearing 11. In order to rotate the inclined shaft 16 from the rotation of bearing 9, shaft 45 16 is provided on its rear end with a pinion 43 meshing with a pinion 44 fixed on the stationary shaft 12. So that as the bearing 9 rotates about shaft 12, pinion 43 will revolve around pinion 44 which is stationary 50 and will be positively rotated to turn the inclined shaft 16. This combined rotation of bearing 9 and inclined shaft 16 produces the desired wobbling movement of the member 28 carried on the chuck 21. 55 The rotatable member 9 at the opposite side of the axis of the fixed shaft 12 from the shaft 16 and gear wheel 43 is provided with a weighted member 43^a, which counterbalances the parts so that this member 9 will 60 rotate with little or no vibration. The rotatable member 9 is in part supported by this fixed shaft 12 and in part supported by the bushing 11 in the frame of the machine, and the shaft 16 extends through a 65 portion of the member 9 which is located in

the bushing 11. This greatly facilitates the positioning of the parts so that the axis of the shaft 16 intersects the axis of the stationary shaft 12 and the axis of rotation of the member 9 at the center of the ball which is being lapped.

It will be noticed that due to the stationary bearing 11, the bearing 9 is given a firm rotation so that the inclined shaft 16 carried thereby is also firmly held and the consequent rotation of shaft 16 is free from vibrational strains and movements occasioned by the lapping operation. This is most important—this construction whereby the chuck 21 is firmly supported during its wobbling movement inasmuch as the lapping of the members must be precise.

The other cooperative member to be lapped is firmly held in a bracket or work holder in proper position with respect to the member 23. To this end, the casting 1 is formed with a slotted arm 45 in which is adjustably mounted, as by means of a nut 46, the stud 47. The other end of the stud is similarly mounted. Stud 47 has pivotally mounted thereon the work supporting arm 48 having a recess 49, in which is mounted the strap or shell 50 which is the other member to be lapped. This shell 50 is held from swinging outwardly by the set screws 51 and lock nuts 52 located at the outer face of the work supporting arm. Work supporting arm 48 is supported on a stud 53 which bears against the lower portion of the casting 1. For the purpose of removing the work, that is, the shell 50, the work supporting arm 48 may be swung upwardly. A cover 53 is pivoted at 54 to the casting. This cover houses the work supporting members and excludes dirt and dust from the lapping members during their relative movement. This cover 53 may be lifted by a pin 55 and is held in a predetermined lifted position by the stop 56.

It will be noted that in the machine, as above described, all working parts are enclosed and that each individual machine is driven from the power shaft by means of a clutch. It will also be noted that the ideal lapping position of the ball 22 and strap 50 is such that the center of the ball coincides with the axes of both the rotating bearing 9 and the rotating inclined shaft 16. The strap 50 of course, being held from rotation during the wobbling movement of the ball. The arrangement herein produces a more accurately lapped joint in a much shorter time than any known previous arrangement.

The draw pin 26 is provided with a rectangular head 26^a, to which a wrench may be applied through an opening 26^b in the casting 13. This makes very ready means for adjusting the draw pin 26 for moving the chuck sleeve 20 to cause the chuck fingers to grip the shank of the member carrying the

ball which is to be lapped. The device described above is particularly useful in connection with the lapping of ball and socket joints. The shank of the ball member is inserted in the chuck 20, and the jaws 21 of the chuck tightened on to the shank through the aid of the draw pin 26. This firmly clamps the ball member. The socket member of the joint is placed in the recess 49 after the manner indicated in Figure 2, and clamped therein by the bolts 51. Of course, the socket is placed on the ball. It will be noted that the axis of the shaft 16 and the axis of the stationary shaft 12 on which the bearing member 9 rotates intersect each other substantially at the center of the ball which is to be lapped. After the parts have been placed in the machine after the manner stated, the ball and socket are flooded with a mixture of oil and a grinding compound. When the parts have been sufficiently ground or lapped by this first compound, they are taken apart, washed, and placed in another machine of the same type and lapped as before with the final compound. They are then taken apart and washed again, and finally lapped in still another machine, or in the same machine, without any compound at all. This results in a burnishing of the surfaces of the ball and socket.

It is obvious that minor changes in the details of construction and the arrangement of the parts may be made without departing from the spirit of the invention as set forth in the appended claims.

Having thus described the invention, what I claim as new and desire to secure by Letters-Patent, is—

1. In a machine for lapping ball and socket joints, the combination of a supporting frame, a rotatable member mounted on said frame, means for rotating said member, a rotatable shaft carried by said member and disposed at an acute angle to the longitudinal axis of said rotatable member, means whereby said rotatable member as it rotates, rotates said shaft, said rotatable member and said shaft being so disposed relative to each other that their axes intersect each other at the center of the ball being lapped.

2. In a machine for lapping ball and socket joints, the combination of a supporting frame, a rotatable member carried by said frame, means for rotating said member including a clutch, a shaft carried by said member and disposed at an acute angle to the axis of said member, whereby as said member is rotated, said shaft will be carried bodily therewith, means whereby the rotation of said member imparts rotations to said shaft, means carried by said shaft for supporting the ball to be lapped, and means carried by the frame for supporting the socket in engagement with said ball.

3. In a machine for lapping ball and

socket joints, the combination of a supporting frame, a rotatable member carried by said frame, means for rotating said member including a clutch, a shaft carried by said member and disposed at an acute angle to the axis of said member, whereby as said member is rotated, said shaft will be carried bodily therewith, means whereby the rotation of said member imparts rotations to said shaft, means carried by said shaft for supporting the ball to be lapped, and means carried by the frame for supporting the socket in engagement with said ball, the axis of said shaft and the axis of said rotatable member being so disposed as to intersect at the center of the ball being lapped.

4. In a machine for lapping ball and socket joints, the combination of a supporting frame, a fixed shaft carried thereby, a rotatable member mounted at one end on said fixed shaft and rotatable thereon and mounted at its other end in a bushing which surrounds said rotatable member, means for rotating said member, an inclined shaft mounted in said rotatable member and extending through said bushing to a point beyond the end of said rotatable member, means for mounting the ball on the end of said shaft, means whereby said rotatable member rotates said shaft, means carried by the frame for supporting the socket which is to be lapped with said ball, said inclined shaft and said rotatable member being so disposed relative to each other that their axes intersect in the center of the ball being lapped.

5. In a machine for lapping ball and socket joints, the combination of a supporting frame, a fixed shaft carried thereby, a rotatable member mounted at one end on said fixed shaft and rotatable thereon and mounted at its other end in a bushing which surrounds said rotatable member, means for rotating said member, an inclined shaft mounted in said rotatable member and extending through said bushing to a point beyond the end of said rotatable member, means for mounting the ball on the end of said shaft, a gear secured to the inclined shaft, a gear secured to the inclined shaft and meshing with the fixed gear whereby said rotatable member as it rotates causes the inclined shaft to rotate, means carried by the frame for supporting the socket which is to be lapped with said ball, said inclined shaft and said rotatable member being so disposed relative to each other that their axes intersect in the center of the ball being lapped.

6. In a machine for lapping ball and socket joints, the combination of a supporting frame, a rotatable member, a fixed shaft carried by the frame and extending into one end of said rotatable member, a bushing carried by the frame and surrounding the other end of said rotatable member whereby said

member rotates on said shaft and in said bushing, an inclined shaft mounted in said rotatable member and extending through the bushing and beyond the end of said rotatable member, means for clamping the ball at the end of said shaft, a supporting bracket carried by the frame, on which the socket is mounted in which said ball is to be lapped, means whereby said rotatable member as it rotates, rotates the inclined shaft, the axis of said rotatable member and the axis of said inclined shaft intersecting in the center of the ball being lapped.

7. In a machine for lapping ball and socket joints, the combination of a supporting frame, a rotatable member, a fixed shaft carried by the frame and extending into one end of said rotatable member, a bushing carried by the frame and surrounding the other end of said rotatable member whereby said member rotates on said shaft and in said bushing, an inclined shaft mounted in said rotatable member and extending through the bushing and beyond the end of said rotatable member, means for clamping the ball at the end of said shaft, a supporting bracket carried by the frame, on which the socket is mounted in which said ball is to be lapped, means whereby said rotatable member as it rotates, rotates the inclined shaft, the axis of said rotatable member and the axis of said inclined shaft intersecting in the center of the ball being lapped, means for pivotally supporting the bracket carrying the socket member, and an adjustable stop carried by said bracket for positioning the same relative to the rotatable member.

8. In a machine for lapping ball and socket joints, the combination of a supporting frame, a rotatable member, a fixed shaft carried by the frame and extending into one end of said rotatable member, a bushing carried by the frame and surrounding the other end of said rotatable member whereby said member rotates on said shaft and in said bushing, an inclined shaft mounted in said rotatable member and extending through the bushing and beyond the end of said rotatable member, means for firmly holding 35 said socket member from turning on the ball while it is being lapped.

8. In a machine for lapping ball and socket joints, the combination of a supporting frame, a rotatable member, a fixed shaft 40 carried by the frame and extending into one end of said rotatable member, a bushing carried by the frame and surrounding the other end of said rotatable member whereby said member rotates on said shaft and in said 45 bushing, an inclined shaft mounted in said rotatable member and extending through the bushing and beyond the end of said rotatable member, means for clamping the ball at the end of said shaft, a supporting bracket 50 carried by the frame, on which the socket is mounted in which said ball is to be lapped, means whereby said rotatable member as it rotates, rotates the inclined shaft, the axis of 55 said rotatable member and the axis of said inclined shaft intersecting in the center of the ball being lapped, means for pivotally supporting the bracket carrying the socket member, and an adjustable stop carried by said bracket for positioning the same relative to the rotatable member.

In testimony whereof, I affix my signature.

ARVID ERICSSON.
